UNITED STATES PATENT OFFICE.

WILLIAM F. CONKLIN, OF LEECHBURG, PENNSYLVANIA, ASSIGNOR TO
WEST LEECHBURG STEEL CO., OF PITTSBURG, PENNSYLVANIA, A
CORPORATION OF PENNSYLVANIA.

METAL COILING AND STRAIGHTENING APPARATUS.

No. 823,765.

Specification of Letters Patent.

Patented June 19, 1906.

Application filed August 4, 1904. Serial No. 219,559.

To all whom it may concern:

Be it known that I, WILLIAM F. CONKLIN, a resident of Leechburg, in the county of Armstrong and State of Pennsylvania, have 5 invented a new and useful Improvement in Metal Coiling and Straightening Apparatus; and I do hereby declare the following to be a full, clear, and exact description thereof.

My invention relates to apparatus for coiling and straightening, stretching, or drawing steel, brass, copper, or other metal strips, rods, or wire, its main object being to provide suitable apparatus to receive the same from rolls or dies and coil the same under 10 tension, either drawing the strips through the rolls or dies or receiving the same from driven rolls, as may be desired. By this apparatus I am enabled to grip the strips and at the same time expand a reel on which the 15 strip is coiled, to control the coiling operation, keeping the material in perfect alinement and holding the strip as coiled under tension and pressure, and to hold the material in coil until it is clamped or bound together ready to be released from the reel.

The special improvements embodied in the invention include the combination, with metal-reducing devices, rolls, or dies, of a power-driven expansible reel having a clamp 20 for engaging the strip and so drawing it under tension as it is wound upon the reel.

It also includes certain improvements in the construction of the reel and the clamping device by which they both can be operated 25 by a single motion.

It also consists in pressure devices operating the strip as reeled to hold it to place as it is coiled.

It also consists in certain lever and clutch 30 connections for controlling the movable parts and in certain other improvements, all of which will be hereinafter described and claimed.

To enable others skilled in the art to make 35 and use my invention, I will describe the same more fully, referring to the accompanying drawings, in which—

Figure 1 is a side view, partly in section, illustrating the invention. Fig. 2 is an end 40 view of the apparatus, illustrating also the rolls or dies with which it may be employed. Fig. 3 is a cross-section on the line 3 3, Fig. 1. Fig. 4 is a longitudinal section of the reel.

Fig. 5 is a vertical cross-section thereof on the line 5 5, Fig. 4. Figs. 6 and 7 are like 55 views illustrating the coiling and clamping of the strips, and Fig. 8 is an enlarged cross-section of the cam-bar.

The apparatus is supported upon a suitable base or frame 1, having bearings 2 3, in 60 which is mounted the main shaft 4, carrying at one end the reel 5. This reel may of course be driven by any suitable power connection. The apparatus illustrated is found, however, the most desirable, and I will therefore describe the same. Mounted loosely upon the main shaft 4 is the driving-wheel 6, driven by any suitable power and having the clutch-face 7, formed on the inner side of its rim 8. Supported on the bed-frame 1 is the 65 stationary clutch face or member 9, the same being formed of a frame 10, secured to and extending up from the main frame 1 and having a bearing 11, fitting around the main shaft 4 to hold the stationary clutch member 70 75 in proper line. Between the clutch member 7 and the clutch member 9 is mounted the sliding clutch 12, which has a feather-and-groove connection 13 with the main shaft 4 and is provided with the clutch face 14, engaging with the clutch-face 7 of the driving-wheel 6 and the clutch-face 15, engaging with the stationary clutch member 9. This mechanism provides for the quick rotation of the reel 5, carried on the main shaft—that is, 80 as soon as the strip to be drawn is connected therewith—and also for the quick stopping of the reel as soon as the strip is wound thereon, so that the reel is under practically 85 perfect control.

The sliding clutch member 12 is operated through a suitable lever 16, engaging with a collar 17 and controlled by the treadle 18, which has a toggle-lever connection 19 with the lever 16, the lever 16 carrying the weight 90 95 21 to throw the clutch from connection with the driving-wheel 6 into the stationary clutch member 9 when the treadle 18 is raised. The treadle 18 is rigidly secured to the shaft 22, which also has rigidly secured thereto the toggle-arm 20, and the treadle may be locked in its lowest position by means of the spring-catch 24. The apparatus also provides for the control of the coiling of the strip through the friction-clutch connection with the driving-wheel 6. The tog- 100 105

gle-arm 19 is formed of the right and left hand nut 23, engaging correspondingly-threaded bars, thus providing through the longitudinal adjustment of this toggle-arm 5 for the regulation of the friction of the clutch, and thereby for the regulation of the tension on the material being coiled.

The reel for coiling the strip is adapted to grip the strip and hold the same firmly, so as 10 to apply the necessary pressure to the strip to coil or wind it under tension, the operation of which leads to the straightening or stretching of the strip, while, if necessary, sufficient power can be applied to draw the strip under 15 tension through the reducing rolls or dies, the necessary power for drawing and finishing the strip being thus provided. The apparatus for such purpose is illustrated in the drawings, and I will now describe the same. 20 The reel 5 is carried on the end of the main shaft 4 and has the hub or spider 25, the inner disk or plate 26, and the outer disk or front plate 27, and between these disks the expandible reel-sections 32 and 33, the reel-section 32 being secured by bolting to the 25 disks 26 and 27. The disks are also secured to the hub or spider 25. Mounted in the inner and outer plates 26 27 is the cam-bar 28, which can be turned by a suitable removable 30 hand-crank 29, this cam-bar having, as illustrated, the eccentric clamping-face 30 along one edge and the cam-face 31 along the edge opposite thereto. The winding portion of the reel 5 is formed in two sections, the reel-section 32 being rigid with the main reel-body and clamped between the inner and outer plates 26 27, while the reel-section 33 is mounted to slide between said inner and outer plates, and so provides for expanding 35 and collapsing the reel. The reel-sections 32 and 33 are each provided with recesses at their ends, which together form the recesses 34, providing for the binding of the coiled strip or rod by suitable clamps or clips before 40 it is removed from the reel. The stationary section 32 has also the slot 35 for the entrance of the end of the strip or rod, as illustrated at 36, and within the said slot 35 and opposite the clamp-face 30 of the cam 28 is the bearing-face 37, the end of the strip being clamped 45 between said face and the clamping-face 30 of the cam, as illustrated.

The sliding reel-section 33 is preferably mounted as follows: On opposite sides of the hub 25 are formed guideways 38, and the reel-section 33 has the guide-arms fitting in the guideways, these guide-arms being connected above or on the opposite side of the hub from the main body of said reel-section 55 33 by the plate 40, upon which the cam-face 31 of the cam 28 bears, as illustrated. A spring 41 is interposed between said plate 40 and the hub 25, which operates to raise the reel-section 33 and so collapse the reel, and 60 holds it in such position, except when oper-

ated upon by the cam 28. The turning of said cam 28 therefore serves the double function of clamping the strip in the reel between the eccentric face 30 of the cam-bar 28 and the clamping-face 37 of the reel-section 32 70 31, bearing upon the plate 40.

In the operation of reeling the strips it is desirable, as above stated, to hold the strip under compression during reeling and to 75 bind it firmly in place until it may be bound by suitable clips and so held ready for removal from the reel. To accomplish this, I provide the lever 42, carrying at its end the roller 43, adapted to contact with the strip 80 being coiled, the lever and its roller being held in contact by means of the spring 44, connecting with the short arm of the lever 42 by means of a rod 45. The spring 44 is held in a suitable yoke 46, secured to the bed-frame 1, and is withdrawn by means of the treadle 47 and connecting-rod 48, said treadle being held in its lowest or withdrawn position by means of the spring-catch 49. It is desirable in the operation of such reeling mechanism to hold the reel in position for receiving the strip as it comes from the rolls or dies, and for that purpose I form in the edge of the inner disk 26 of the reel-body the notch 50, with which a spring-pawl or stop-catch 51, mounted on the main frame at 52, engages. Depending from this catch is the yoke 53, which, as shown, fits around the treadle 18, operating the clutch mechanism, this yoke being of such size that when the treadle 18 is depressed to connect the clutch with the driving-wheel 6 the base of the treadle first engages with the base of the yoke 53 and withdraws the catch 51, leaving the reel free to turn; but, as soon as the treadle 18 is raised 100 and the weight 20 caused to throw the clutch into engagement with the stationary clutch 9 this stop-catch 51 is free to act, and it engages with the notch 50 of the reel and so holds the reel in the proper position for receiving the 105 next strip. The spring-catches 24 and 49 are of the same construction and on the same line, and the spring-catch 24 (shown in Fig. 1) is intended to engage with the treadle 18, which in said figure is shown in its raised position. 110

When the apparatus above described is employed in the reeling of strips, its operation is as follows: The operation being practically the same in the reeling of wire rods, though, if desired, suitable mechanism for guiding the coiling of the rod upon the reel may be employed, the strip 36, either fed by power or drawn through the rolls 54 or through dies 55, (illustrated diagrammatically in dotted lines,) is inserted into the slot 35 of the reel, and by turning the cam 28 the strip is clamped to the reel and the reel expanded, as illustrated in Figs. 3 to 5. The treadle 18 is then forced down- 115 120 125 130

wardly, throwing the clutch member 12 into engagement with the driving-wheel 6, while the treadle 47 is released, so that as the reel turns the roller 43 may contact with the strip and control the coiling of the same upon the reel under pressure of the spring mechanism 44. The depression of the treadle 18 also withdraws the pawl or stop 51 from the notch 50, leaving the reel free to turn. The speed of the reel is such that it acts to wind the strip under tension or to draw it through the dies, the drawing strain being regulated according to the material operated upon and by the slip of the friction-clutch and the material during coiling being compressed against the reel by the spring-roller 43. As soon as the strip is drawn entirely from the rolls or dies and entirely coiled upon the reel the treadle 18 is released, when through the weights 20 operating on the clutch-lever 16 the clutch is thrown into contact with the stationary clutch member 9, stopping the rotation of the reel, and this same movement frees the stop-catch 51, which engages with the notch 50 in the rim of the reel, the reel being thus stopped in proper position for the reeling of the next strip. After the strip is reeled, and to prevent the uncoiling thereof, the pressure-roller 43 is held in contact with the coiled strip until the operator can insert suitable metal clamps or clips 56 through the recesses 34 of the reel and bind the coil by means of the same, after which the treadle 47 is depressed, withdrawing said pressure-roller from contact with the rolls. In order to release the coil, it is then only necessary to turn the cam 28, mounted in the reel-body, which releases the forward end of the strip, and at the same time through the spring 41 the movable reel-section 33 is drawn toward the stationary section 32, thus collapsing the reel and leaving the coil free to be withdrawn therefrom. The several operations can be quickly performed by a workman standing at the side of the reel ready to both operate the cam 28 and the different levers, as above described.

The apparatus has been found valuable for the reeling of thin metal strips, rods, or wire and to work efficiently and rapidly. It is of special advantage in straightening, coiling, and flattening thin metal strips delivered from dies; rolls, slitting-machines, &c., as, in addition to coiling the same under tension and in that way insuring a perfectly straight strip, it keeps the material in perfect alignment while passing through the rolls or other machines and winding upon the reel under tension, so insuring a perfectly straight strip, no matter what its length may be, and dispensing with the necessity of stretching-machines for straightening the material after it has been rolled, slit, or flattened. The tension upon the metal can be regulated at will through the adjustment of the friction-clutch

mechanism, and the strip as delivered is held tightly coiled until it can be clamped ready for withdrawal from the apparatus, while the apparatus is automatically brought to and held in proper position for receiving the strips.

In the following claims the term "strip" includes any material with which the apparatus is adapted for use, such as narrow metal strips, rods, or wire, &c.

75

What I claim is—

1. In apparatus for coiling metal strips, the combination of an expansible reel provided with a slot for the entrance of the strip, mechanism mounted in said reel arranged to both engage the strip and clamp the same and to expand the reel, and a driven shaft on which said reel is fixedly mounted.

2. In apparatus for coiling metal strips, the combination of a reel having a stationary section and a movable section and provided with a slot for the entrance of the strip, a cam mounted in said reel between said sections and arranged to press the strip against the stationary section to clamp the same and also engage the movable section to expand the reel, and a driven shaft on which said reel is fixedly mounted.

3. In apparatus for coiling metal strips, the combination of a reel-body secured upon a driving-shaft and having a hub provided with guideways, a stationary reel-section, and a sliding reel-section having guide-arms engaging with the guideways of the hub.

4. In apparatus for coiling metal strips, the combination of a reel-body secured upon a driving-shaft and having a hub provided with guideways, a stationary reel-section, a sliding reel-section having guide-arms engaging with the guideways of the hub, and a connecting-plate between said guide-arms and a spring confined between the hub and plate for contracting the reel.

5. In apparatus for coiling metal strips, the combination of a reel-body secured upon a driving-shaft and having a hub provided with guideways, a stationary reel-section, a sliding reel-section having guide-arms engaging with the guideways of the hub, a connecting-plate between said guide-arms, a spring confined between the hub and plate for contracting the reel, and a cam engaging with the connecting-plate for expanding the reel.

6. In apparatus for coiling metal strips, the combination of a frame, a shaft mounted therein and carrying a reel, a driving-wheel fitting around said shaft and having a clutch-face, a stationary clutch member supported on the frame, a sliding clutch connected with said shaft and adapted to engage the driving-wheel and stationary clutch member, a treadle arranged to move the clutch into engagement with the driving-wheel, and automatically-acting means for throwing said clutch into engagement with the stationary clutch mem-

130

125

120

115

110

ber, and a lock for holding said last means inoperative.

7. In apparatus for coiling metal strips, the combination of a frame, a shaft mounted therein and carrying the reel, a driving-wheel fitting around said shaft and having a clutch-face, a stationary clutch member supported on the frame, a sliding clutch connected with said shaft and adapted to engage the driving-wheel, and the stationary clutch member, the clutch-lever 16 carrying the weight 21 and the treadle 18 having the toggle connections 19 20 with the clutch-lever.

8. In apparatus for coiling metal strips, the combination of a frame, a shaft mounted therein and carrying the reel, a driving-wheel fitting around said shaft and having a clutch-face, a stationary clutch member supported on the frame, a sliding clutch connected with said shaft and adapted to engage the driving-wheel and the stationary clutch member, the clutch-lever 16 carrying the weight 21 and the treadle 18 having the toggle connections 19 20 with the clutch-lever, the toggle-link 25 19 being longitudinally adjustable.

9. In apparatus for coiling metal strips, the combination of a power-driven reel and a spring - operated pressure - roller mounted therewith and adapted to contact with the material coiled upon said reel, a treadle and connections between the spring-pressure roller

and treadle, and a spring-catch for holding the treadle.

10. In apparatus for coiling metal strips, the combination of an expansible reel having 35 clamping mechanism for engaging the strips, and recesses formed therein for binding the coil, and a pressure-roller adapted to engage the material coiled upon the reel.

11. In apparatus for coiling metal strips, 40 the combination of an expansible reel having clamping mechanism for engaging the strips, and recesses formed therein for binding the coil, a pressure-roller adapted to engage the material coiled upon the reel, and locking 45 mechanism adapted to engage with the reel.

12. In apparatus for coiling metal strips, the combination with a power-driven reel, a pressure-roller coöperating therewith, a lever carrying said roller, a yoke in which said lever is mounted, a spring carried by said yoke and connected to said lever, and a treadle 50 also connected to said lever and arranged to move the lever against the tension of the spring.

In testimony whereof I, the said WILLIAM F. CONKLIN, have hereunto set my hand.

WILLIAM F. CONKLIN.
